UNITED STATES PATENT OFFICE.

CHARLES H. ROSSEEL, OF WORCESTER, MASSACHUSETTS.

AUTOMATIC STABILIZER FOR FLYING-MACHINES.

1,362,965.

Specification of Letters Patent. Patented Dec. 21, 1920.

Application filed January 12, 1918. Serial No. 211,536.

To all whom it may concern:

Be it known that I, CHARLES H. ROSSEEL, a citizen of the United States of America, residing at Worcester, in the county of 5 Worcester and State of Massachusetts, have invented certain new and useful Improvements in Automatic Stabilizers for Flying-Machines, of which the following is a specification, reference being had therein to the 10 accompanying drawings.

This invention relates to an automatic stabilizer for flying machines, and more particularly to a new and efficient pendulum actuated device for the prevention of a flying 15 machine from accidentally falling.

The principal object of my invention is the provision of novel and efficient means for stabilizing or automatically controlling a flying machine for preventing accidents 20 when a machine equipped with a mechanism constructed in accordance with my invention is suddenly acted upon by a gust of wind or by variable air currents as is often encountered in flying.

With this and other objects in view my 25 invention consists of certain novel combinations, constructions and arrangements of parts as will be hereinafter fully described and claimed.

30 In the drawings:—

Figure 1 is a top plan view of a flying machine with my improved mechanism attached thereto.

Fig. 2 is a top plan view of a mechanism 35 constructed in accordance with the present invention.

Fig. 3 is a vertical sectional view, taken on line 3—3, Fig. 2.

Fig. 4 is a horizontal sectional view of 40 the mechanism shown in Fig. 2.

Fig. 5 is a vertical sectional view taken on line 5—5, Fig. 2.

Fig. 6 is a fragmentary sectional view of 45 the pendulum device.

Fig. 7 is a fragmentary view in side elevation of a modified form of my invention showing particularly the beveled gear on the drive shaft below the beveled gears of the driven shafts.

50 Fig. 8 is a view in side elevation of the clutch, while

Fig. 9 is a fragmentary sectional view of the clutch, looking at the rear thereof.

Fig. 10 is a view in side elevation of the 55 locking dog of the clutch.

Fig. 11 is a sectional view taken on line 11—11, Fig. 5.

Fig. 12 is a fragmentary view in side elevation of the primary section of the clutch.

Fig. 13 is a sectional view taken on line 13—13, Fig. 3.

Fig. 14 is a sectional view taken on line 14—14, Fig. 3.

Fig. 15 is a perspective view of the locking frame of the mechanism.

Fig. 16 is a sectional view taken on line 16—16, Fig. 3.

Fig. 17 is a fragmentary sectional view of another embodiment of my invention, while

Fig. 18 is a fragmentary top plan view of 70 the embodiment shown in Fig. 17.

Fig. 19 is a fragmentary, longitudinal sectional view through the ratchet sleeve.

Fig. 20 is an end elevation of one part of 75 the ratchet sleeve.

After considerable investigation I have invented the following described mechanism for making flying machines safe under all conditions, irrespective as to whether the engine or motor becomes inoperative, when 80 the machine is under the greatest stress, or whether the air currents vary, causing gusts of wind or undue strain to be placed upon the planes while the machine is in the air.

In the accompanying drawings I have 85 shown the preferred embodiment of my mechanism, and have illustrated in Fig. 1 the application of my invention to a flying machine of the bi-plane type, but my mechanism is susceptible of adaptation to many 90 different types of flying machines since the principle of operation is the same, although there might be some slight change or alteration in the connecting means between my stabilizing mechanism and the parts of the 95 machine governed for controlling the same.

Referring to the drawings by numerals 1 designates the frame of the machine to which is secured the inner bracket frame or casing 2 and the outer bracket or bearing 100 frame 3. These frames 2 and 3 illustrate bearings for the parts hereinafter described, and said frames 2 and 3 are suitably bolted or otherwise preferably detachably secured to the frame of the flying machine.

The driving shaft 4 is journaled upon the frame 2, being prevented from sliding down upon the frame 2 by the usual locking collar 5, Fig. 3.

The driving shaft 4 is provided with a 110

gear 6 meshing with worm gear 7, which worm gear 7 is keyed to shaft 8, and secured to shaft 8 is a large pinion wheel 9. The engine shaft 10 is provided with a gear 11 meshing with the pinion 9, and through this just described arrangement of gears, pinions and shafts rotary movement is imparted to the driving shaft 4 preferably from the engine, although it will not be departing from the spirit of this invention to have connected up to driving shaft 4 an auxiliary motor or engine so that if the primary engine should become inoperative, for any reason whatsoever, the auxiliary motor or engine could be started by the operator of the machine and the stabilizing effect be procured while the main or primary engine was inoperative.

Fixedly secured to the driving shaft 4 is beveled gear 12, which gear 12 meshes with preferably four beveled gears 13. Each gear 13 is fixedly secured or keyed to a primary driven shaft 14, and as each primary driven shaft 14 and its coöperating parts are similarly constructed, it will only be necessary to specifically describe one of the shafts 14, one of the clutches associated therewith and one of the friction drum sleeves and its coöperating parts. It is to be understood, upon referring to Fig. 4 that I have employed four of these coöperating clutch and friction drum sleeve devices in the embodiment described in this application and consequently it would be superfluous to describe each one separately, as the description of one will suffice.

The primary driven shaft 14 is journaled in the lower portion of the frame 2, Fig. 3, and preferably mounted upon the ball bearing of any preferred type, and to the inner end of shaft 14 is secured the primary section 15 of the clutch. The primary section 15 of the clutch is provided with an annular rim 16, in the inner edge of which rim 16 are a series of receiving pockets or sockets 17, Fig. 12, that are adapted to receive the semi-cylindrical extension 18 of the shaft portion 19 of the locking dog (Fig. 10) of the clutch. The shaft portion 19 of the locking dog is integral with the body portion 20, which body portion 20 is provided with an apertured ear 21 (Fig. 9) and is provided also with a cam face 22 and a socket 23. A coil spring 24 is fastened at one end in the aperture of the ear 21 and by means, preferably by means of a screw, 25 is fastened at its other end to the auxiliary section 26 of the clutch so that the tendency at all times is for the spring 24 to rotate the locking dog sufficiently to cause the semi-cylindrical end 18 to enter a pocket or socket 17 of the primary section 15 of the clutch, as shown by dotted lines 18' of Fig. 12.

The auxiliary section 26 of the clutch is fastened to the auxiliary driven shaft 27,

which auxiliary shaft 27 is mounted upon suitable ball bearings 28 carried by the journaled-bracket-frame 3, Figs. 3, 4, and 5. This auxiliary driven shaft 27 is keyed in a bushing or hub portion 29 of the auxiliary section 26 of the clutch, the auxiliary section being provided with an outer ring or section 30, Fig. 5, and upon the auxiliary section 26 is mounted the locking dog hereinbefore referred to. 75

In the bracket frame 3, at 31, is formed a suitable pocket for a lubricant, and on the auxiliary driven shaft 27 is a loosely mounted lubricant ring 32.

A ratchet sleeve 33 is mounted upon the auxiliary driven shaft 27, and surrounding the ratchet sleeve 33 is a friction sleeve 34, which friction sleeve 34 is provided with a pair of semi-circular brake bands 35, the frictional resistance of the semi-circular bands being governed by the screws 36. Cables or connecting means 37 are attached to the frictional control drum sleeve 34 through the medium of the eye-bolts 38.

Two sets of the cables 37 are connected to the wing-flaps 39, one cable of one set being connected to a flap at one end of the plane and the other cable of the set being connected to a flap at the other end of the plane, so that when the drum sleeve 34 is rotated automatically the wing-flap at one end of the plane will be swung or warped into a vertical position opposite to the wing-flap at the other end of the plane actuated by the other companion cable of the set 100 on the same drum sleeve. Of course, it is to be understood that the wing flaps are interconnected in the usual manner so that when one is lowered, the other may be raised and, therefore, the cables which extend to the wing flap on one side of the plane raise this flap, while the cables which extend to the wing flap on the opposite side of the plane lower the same. 95

Besides the two drum sleeves carrying each a pair of cables that operate the two sets of wing-flaps on the plane, I have provided two drum sleeves that carry cables or connecting means 38^a, Fig. 2, which control the automatic movement of the wing-flaps 40 of the tail-piece of the machine. Each cable 38^a being fastened at one end to one of the drum sleeves and being fastened at its other end to another drum sleeve so that the warping or movement of the tail-flaps 40 will automatically be controlled when the drum sleeves are rotated by the action of the mechanism more fully hereinafter described. 115

The frictional resistance of the drum sleeve 34 upon the ratchet sleeve 33 is sufficient under ordinary conditions to permit the satisfactory winding of the two cables connected thereto upon the sleeve, but if the engine is running at too great a speed 130

there will be permitted a sufficient "give" or sliding rotary movement of sleeve 34 with respect to ratchet sleeve 33 to relieve the undue strain and thereby not injuring the mechanism when undue or uncalled for strain is placed upon the cables and their respective drum sleeves 34.

In each ratchet sleeve 33 is a loosely mounted pin or pawl member 41 that is provided with a head 42, Fig. 5, working in a suitable slot 43 so that while the ratchet sleeve 33 travels in one direction, the sleeve will be locked in its rotary movement with respect to the auxiliary driven shaft 27, but when, the machine has returned to within the number of degrees the control is set at, allows the ratchet sleeve 33 to rotate backward, unwinding cable automatically and allowing the wing-flaps to close.

Referring particularly to Figs. 19 and 20, and to Fig. 5, it is pointed out that the ratchet sleeve 33 will be locked to the auxiliary driven shaft 27 by the engagement of the pawl head 42 with the abrupt portion 42' of the ratchet, but when the sleeve 33 rotates in the opposite direction, the cam portion 43' of the ratchet will move the pawl 41 longitudinally of the auxiliary shaft so that the head will be located in the recess 44' in the ratchet sleeve, (see Fig. 19). Thus the sleeve, when rotating in one direction may have movement independent of the auxiliary drive shaft, but when the movement is in the opposite direction the drive shaft and the sleeve will move as a unit.

It is to be noted that the ratchet sleeve 33 will be locked to the auxiliary driven shaft 27 when said shaft becomes clutched to the main driving shaft, upon the tilting of the machine to one side or the other throwing in the corresponding clutch. The rope drum sleeve 34 being in frictional engagement with ratchet sleeve 33, said drum sleeve will also be rotated and thereby wind the wing flap cables thereon and thereby operate and control the movements of said flaps to check the further tilting of the machine and subsequently bring the machine back to its normal position. When the machine is righted and the clutch disengages the auxiliary shaft from the main shaft, the ratchet sleeve 33 will also become disengaged from the auxiliary shaft, which will allow the ratchet sleeve to rotate in a reverse direction to the direction of rotation of the auxiliary shaft upon the unwinding of the cables caused by the wing flaps returning to their normal position.

The lower end of the drive shaft 4 is threaded as shown in Figs. 3 and 6, and mounted upon the threaded end is a hollow ball member 44, that is held upon the threaded end of the shaft against displacement by means of a locking pin 45. The

pendulum casing 46 is suitably weighted, as indicated at 47, and the casing 46 is provided at its upper end with a flange 48 upon which flange 48 rests the cap 49. The cap 49 is detachably secured to flange 48 of the pendulum casing by means of bolts 50. The cap 49 is provided with a central opening 51, through which the threaded end of the drive shaft 4 extends, Figs. 3 and 6, and this cap 49 is provided with an annular ring, holding ball bearings 52 in position, bearing against the outer face of the hollow ball member 44, thereby supporting the pendulum casing 46 freely upon the hollow ball member 44 so that the pendulum casing 80 is free to swing upon the lower end of the drive shaft for actuating the trigger fingers 53 of the trigger devices carried by the inwardly projecting extensions 54 of the auxiliary bearing brackets or frame 3. Each 85 finger 53 is pivotally mounted, at 55, within the socketed or outer bifurcated end of the body 56 of the trigger device. The body 56 is pivotally mounted upon the pin 57, and the inner end of the body 56 is adapted to 90 swing or move over the cam face 22 (Fig. 9) of the locking dog and thence into the socket 23 for holding the semi-cylindrical extension 18 out of the pockets or sockets 17 of the primary section of the clutch, thereby keeping the stabilizing mechanism in an inoperative position until an undue stress is placed upon the planes, causing the machine to tilt or lean or pitch in one direction, resulting in the pendulum casing 100 95 105 110 115 120 125 130 135 140 145 150 155 160 165 170 175 180 machine will have sufficient momentum to carry it several hundred feet, and by using an auxiliary engine to operate the shaft 4, the machine can be quickly righted or "stabilized" for preventing an accident, in the case it is found best to utilize my improved stabilizing mechanism for preventing an accident.

Through the medium of spring 58, attached at 59, Fig. 5, to the extension 54 of frame 3 and attached at 60 to the trigger finger 53, a downward pull is at all times exerted upon the trigger finger 53 resulting in the body 56 of the trigger device being pressed upwardly at its inner end causing the same to quickly seat itself in the socket 23 of the locking dog when the machine is running smoothly in the air. It is only in case of distress or accident or sudden stress being placed upon one side or front or rear of the machine that the pendulum device is operated and the stabilizing mechanism thrown into action.

Before the machine is started off the ground, the adjusting screws 61 are adjusted to a nicety and said screws are locked in position by the locking nuts as shown, thereby securing an adjustment of each trigger finger to such a degree as the mechanician or operator of the machine desires for causing the operation of the pendulum device in the case its protective action is needed.

With machines equipped with my improved stabilizing mechanism, when exhibition exhibits are to be given, or in case the operator or driver of the machine desires to cause the machine to radically ascend or descend, it will be desired to lock the stabilizing device so that the changing of the pitch of the wing-flaps as well as the tail-flaps will not be caused and therefore I have provided a bell crank lever 62, pivotally mounted at 63, Fig. 3, the inner ends of the bell crank lever 62 being provided with a fork or bifurcated portion 63, and upon the ends of the bifurcated portion are suitably mounted rollers 64. These rollers 64 are positioned against the drive shaft 4 (Fig. 16) and engage the underface of the top 65 of the locking frame, which frame comprises said top 65 and preferably four depending fingers 66, Fig. 15. The lower ends of fingers 66 are adapted to engage the top 49 of the pendulum frame or casing 46, thereby holding the casing 46 in true vertical alignment with the drive shaft 4, preventing any one of the trigger fingers 53 from being operated upon while the locking fingers 66 are engaging the top 49. A coil spring 67, Fig. 3, normally exerts a downward pressure upon the locking frame, which is provided with the fingers 66, so that when the lever 62 is released the spring 67 quickly forces 65 the locking frame into engagement with the

pendulum and thereby prevents its movement upon the ball member 44 until the locking device is released, hence permitting the operator of the machine to perform unusual feats with the machine such as "tail-dip," "spiral-dip," etc., without my improved stabilizer device interfering therewith.

In Fig. 7 I have shown the beveled gear 12 at the lower end of shaft 4 so as to mesh with the gears 13 underneath the same, as this arrangement may be found desirable in some cases.

In the embodiment illustrated in Figs. 17 and 18, to the frame 1 of the machine I fasten a suitable casing 68 and to the bottom of casing 68 I detachably secure a supporting plate or member 69, which plate 69 is provided with a central opening 70 and with a ball race-way 71, in which race-way 71 are positioned the ball bearings 72. Supported upon the ball bearings 72 is the dish-like body portion 73 of the pendulum of this modification, to which dish-like body portion 73 is attached the depending weighted portion 74, portions or parts 73 and 74 constituting a weighted pendulum, and extending from the body 73 is an annular flange 75, which flange 75 is provided with vertically aligned apertures 76, in which apertures 76 are positioned the ball bearings 72. Securing means, such as bolts 77 are positioned for fastening the vertically adjustable cap 78 upon the flange 75.

I preferably provide four trigger devices 79 in this embodiment, each trigger device 79 being pivotally mounted at 80, and these trigger devices 79 are very similar in structure to the trigger devices shown in Figs. 3 and 5, hence it will not be necessary to specifically describe these trigger devices 79 as the operation is very similar to the devices shown in the preferred embodiment, although it will be noted that the trigger devices 79 are of one piece each. Further, in the embodiment shown in Figs. 17 and 18 the drive shaft 4 and its coöperating parts 101 are similar to the embodiment of the drive shaft shown in Fig. 7, in which the beveled gear 12 is attached to the lower end of the shaft, placing the gear 12 under the beveled gears 13 as hereinbefore described.

When the flying machine tilts or is suddenly tipped to one side or forward or backward the pendulum shown in Figs. 17 and 18 swings or rocks upon the ball bearing 72, causing one portion of the adjustable cap 120 to engage the nearest trigger finger 79, pressing up upon the inner end thereof and consequently releasing the locking dog of the clutch, permitting the spring of the locking dog to cause the semi-cylindrical extension 18 to move into the first notch 17, locking the two sections of the clutch against independent rotary movement, and consequently locking the respective shafts of the two sections of the clutch together, thereby impart-

ing rotary movement through the different parts to the friction drum sleeve 34 of the respective winding device for the cables as hereinbefore stated. The degree of adjustment of the pendulum and the trigger devices, in the embodiment shown in Figs. 17 and 18, can be accomplished to a nicety by means of positioning the bolts 77 in different apertures 76, as it will be obvious that by lowering the bolts 77 the degree of pitch will be increased, whereas when they are in the position shown in Fig. 17 it will only be necessary for the machine to tilt slightly to cause the pendulum device to rock and engage the trigger finger on that side or portion of the machine that is tilted downwardly.

What I claim is:

1. In a mechanism of the class described, the combination with a frame, of a trigger device carried by said frame, a pendulum device carried by said frame and adapted to actuate said trigger device, a cable device supported by said frame, a clutch device operating with said cable device and being controlled by said trigger device, and means for imparting rotary movement to said clutch device and said cable device when said pendulum device is moved for actuating the trigger device and releasing the clutch.

2. In a mechanism of the class described, the combination with a frame, of a clutch carried by said frame, said clutch comprising a primary and an auxiliary section, a trigger-controlled locking dog carried by said auxiliary section of the clutch and being adapted to lock the primary section against independent rotary movement with respect to the auxiliary section, cable winding means operably secured to said auxiliary section of the clutch, driving means connected to the primary section of the clutch, and means for actuating said trigger device and releasing the locking dog of the clutch when said machine is tilted, whereby the cable winding means is automatically actuated for automatically righting or stabilizing the machine.

3. A clutch for a flying machine stabilizer, comprising a primary and an auxiliary section, said primary section provided with an annular rim and receiving sockets in said rim, said auxiliary section provided with a locking dog, said locking dog provided with an extension terminating in a semi-cylindrical projection, said locking dog also provided with an outer cam surface and with a trigger receiving notch, the semi-cylindrical projection being adapted to move into one of the receiving sockets in the rim of the primary section for locking said primary and auxiliary section against independent rotary movement.

4. A trigger finger device for an automatic stabilizer of the class described, com-

prising a support, a body pivotally mounted upon said support, said body provided with a socketed outer end, a trigger finger pivotally mounted in the socketed end of said body, bolts carried by the socketed ends of said body and having their inner ends engaging opposite portions of the trigger finger, and locking nuts on said bolts and engaging the socketed portions of the end for retaining the trigger finger in an accurate adjusted position with respect to its pivot.

5. In a mechanism of the class described, the combination with a flying machine, of a pendulum device carried by said machine, a locking device carried by said machine and adapted to hold said pendulum device against operation, said locking device comprising a frame provided with depending fingers, and means moving said frame and fingers into engagement with said pendulum device, as the operator of the flying machine desires and means tending to prevent such movement.

6. In a mechanism of the class described, the combination with a frame of a machine, of a pendulum device carried by said frame, of a spring pressed locking frame carried by said frame and adapted to move into engagement with said pendulum device, and a lever in engagement with said spring pressed locking frame for moving the frame out of engagement with said pendulum device and against the torsial strain of the spring.

7. In a mechanism of the class described, the combination with a frame, of a pendulum device carried by said frame, of a sliding locking device carried by said frame and adapted to engage said pendulum device for locking the same against movement, said locking device comprising a frame provided with a plurality of depending fingers, a coil spring interposed between the frame of the locking device, and the first-mentioned frame, and said spring being adapted to normally force the lower or outer ends of the fingers into engagement with the pendulum device, a bell crank lever pivotally carried by said first-mentioned frame, said lever provided at its inner end with a yoke, the ends of said yoke being provided with rollers, and said rollers normally engaging the frame of the locking device, whereby the lever can easily raise the frame and fingers against the action of the spring.

8. In a mechanism of the class described, the combination with a flap, a shaft, a ratchet sleeve mounted upon said shaft, a friction sleeve drum carried by said ratchet sleeve, said friction sleeve drum provided with means for increasing its frictional resistance upon said ratchet sleeve, means connecting said flap to said frictional sleeve

drum, and means for imparting rotary movement to said shaft and thereby causing said connecting means to be wound upon said frictional sleeve drum.

- 5 9. In a mechanism of the class described, the combination with a frame, of a flap supported upon said frame, a winding device carried by said frame, said winding device including a ratchet sleeve and a frictional sleeve drum, said frictional sleeve drum provided on its inner face with a semi-circular adjustable band, a screw carried by said frictional sleeve drum and in engagement with said band, for adjusting its frictional resistance with respect to said ratchet sleeve, means connecting said winding device to said flap, and means for actuating said winding device for causing the flap to be adjusted in a vertical plane through the connecting means drawing or pulling upon the flap as the winding device is actuated.
- 10 10. In a stabilizer device for an aeroplane, the combination with a plurality of constantly actuated drive shafts, of a plurality of winding drums adapted to be clutched to said shafts and in axial alignment therewith, and a pendulum device positioned intermediate said drums opera-

tive to selectively effect the clutching of said drive shafts to said drums upon the swinging of said pendulum device.

11. A stabilizer for aeroplanes, comprising a drive shaft, a winding drum, a normally inoperative clutch between said drum and shaft, a lever for controlling said clutch, a pendulum adapted to engage the lever to operate the same, and means for varying the position of the lever with respect to the pendulum.

12. A stabilizer for aeroplanes, including a drive shaft, a driven shaft, a ratchet sleeve adapted to be clutched and engaged to said driven shaft automatically, and a winding drum frictionally engaged with said ratchet sleeve.

13. A stabilizer for aeroplanes, including a drive shaft, a driven shaft, a ratchet sleeve adapted to be clutched and engaged to said driven shaft automatically, a winding drum frictionally engaged with said ratchet sleeve, and means for varying the friction between the drum and sleeve.

In testimony whereof I hereunto affix my signature.

CHARLES H. ROSSEEL.
